LUGGAGE CASE OR SIMILAR ARTICLE

Charles S. Gehrie, Montclair, N.J., and Sol Koffler, Providence, R.I.; said Gehrie assignor to said Koffler

Filed Apr. 19, 1967, Ser. No. 6,752

Term of patent 14 years

(Cl. D87—5)

FIG. 1

FIG. 2

FIG. 3

FIG. 1 is a top plan view of a luggage case or similar article embodying our new design;

FIG. 2 is a side elevational view of the luggage case or similar article, the opposite side being a mirror image thereof; and

FIG. 3 is an end elevational view, the opposite end being a mirror image thereof.

The essential features of our design reside in the full line showing thereof.

We claim:

The ornamental design for a luggage case or similar article, as shown and described.
